CLAIM

The ornamental design for a shoe sole, as shown and described.

DESCRIPTION

FIG. 1 is a perspective view of a shoe sole showing the new design;

FIG. 2 is a front elevational plan view of the shoe sole depicted in FIG. 1;

FIG. 3 is a rear elevation plan view of the shoe sole depicted in FIG. 1;

FIG. 4 is a left side elevational plan view of the shoe sole depicted in FIG. 1;

FIG. 5 is a right side elevational plan view of the shoe sole depicted in FIG. 1;

FIG. 6 is a perspective view of another embodiment of the shoe sole of FIG. 1;

FIG. 7 is a front elevational plan view of the shoe sole depicted in FIG. 6;

FIG. 8 is a rear elevation plan view of the shoe sole depicted in FIG. 6;

FIG. 9 is a left side elevational plan view of the shoe sole depicted in FIG. 6;

FIG. 10 is a right side elevational plan view of the shoe sole depicted in FIG. 6;

FIG. 11 is a left side elevational plan view of another embodiment of the shoe sole depicted in FIG. 1; and,

FIG. 12 is a right side elevational plan view of the embodiment of the shoe sole depicted in FIG. 11.

The broken lines in the Figures are for illustrative purposes only and form no part of the claimed design.
